United States Patent

Des. 237,599
Patented Nov. 11, 1975

237,599

PORTABLE ROUND BALE FEEDER

Richard D. Cox, P.O. Box 387,
Carrollton, Mo. 64633

Filed Sept. 26, 1974, Ser. No. 509,707

Term of patent 14 years

Int. Cl. D12—10; D30—03

U.S. Cl. D12—105

FIG. 1 is a perspective view of a portable round bale feeder showing my new design;

FIG. 2 is a side elevational view thereof;

FIG. 3 is an end elevational view thereof;

FIG. 4 is an end elevational view thereof opposite to that shown in FIG. 3; and

FIG. 5 is a top plan view thereof.

I claim:

The ornamental design for a portable round bale feeder, substantially as shown.
